UNITED STATES PATENT OFFICE.

MORRIS O. NOBBE, OF NEWARK, NEW JERSEY.

SEPARABLE CUFF BUTTON.

Application filed September 24, 1926. Serial No. 137,429.

This invention relates to articles of personal wear and adornment, with special reference to cuff buttons, and particularly to those of a separable type.

5 It is one object of the present invention to provide a button of this class which is resistant to attempts at separation by force exerted to pull or push the parts in opposite directions, the parts being detachable only 10 when its interior elements are moved into a definite position by exerting pressure on one of the button faces, one hand only being required.

A further feature is in the provision of a 15 separable cuff button having level, smooth and unbroken faces at each end, alike in appearance except that on the button face which is to be pressed inwardly to separate the parts there can be some distinguishing 20 mark or indication, easy to embellish with various designs and having no projection to catch and interfere with the clothing or any other object.

By the elimination of a knob or other projection extending outwardly beyond the plane of the front face of the button which are common to other cuff buttons of this type, the danger of accidentally opening the button when the arm of the wearer is leaned 30 upon a desk, table, arm chair or other object, and thereby depressing the knob which disengages the clutch inside, is obviated.

As is obvious, the absence of any projection increases materially the scope of designs or other ornamentation and also makes it possible to ornament both button faces identically, thereby decreasing the cost of manufacture and improving the appearance of the article.

40 The elimination of any such projection is a further advantage, because when the faces are of similar appearance it is not necessary to give any time or care to making certain that uniformity of appearance is attained by having the said projections both face either outwardly or inwardly in each cuff. In the device of this application as the faces are similar, the sections with the fixed or depressible faces may be inserted 45 through the button hole in either side of the cuff and perfect uniformity of appearance will be attained.

Another aim is to produce a highly attractive button, capable of tightly clamping 50 the material through which it is passed, thus

preventing loss by displacement, but permitting ready removal at will.

These several objects are attained by the novel construction, combination and arrangement of parts hereinafter described 60 and shown in the accompanying drawing, forming a material part of this disclosure, and in which:

Fig. 1 is a general illustration showing the manner of removing the button with relation to a conventional cuff.

Fig. 2 is a greatly enlarged longitudinal sectional view of an embodiment of the invention.

Fig. 3 is an end view of the button partially broken away.

Fig. 4 is a similar view looking from the opposite end.

Fig. 5 is a side elevational view of the button as disengaged.

As will be noted in Fig. 5, the button consists of two distinct members, A and B, the latter comprising a face 10, ornamented in any desired manner and provided with a backing 11, of slightly less diameter.

The extending annular edge of the face element 10 is seated on the outer surface of a hollow ring or bead 12, the openings therethrough engaging the periphery of the backing 11 and its inner edge 13 engages over an outturned expanded edge of a bell-shaped casing 14 having a short, contracted cylindrical inner end 15.

Engaged in the casing end 15 and extending slightly into its flared portion is a sleeve 16 formed with an outwardly inclined flange 17 terminating in a closed circular bead 18, the same constituting one of the abutting elements of the button member B.

Resting on the inner face of the backing 11 are the forked ends 19 of a trilobed flat spring 20 spaced by its ends from the backing plate and seated on the main central portion of the spring is the back of a second flat spring 21, also having three indent extending prongs 22 reaching normally into the space enclosed by the sleeve 16, this last named spring 21 being held in position by prongs 23 on the spring 20, as best seen in Fig. 2.

The other member A consists of a similar face 25 having an offset annular flange 26 at its periphery in which is a circular back- 100 ing plate 27.

A bead 28, similar to that previously de- 110

scribed, slidably engages over the flange 26 at its outer edge and its inner edge 29 is fitted over the expanded end of another bell-shaped casing 30, having an inner cylindrical end 31 in which is fixed a sleeve 32 formed on an outwardly inclined flange 33 terminating in a circular bead 34, opposed to the mating bead 18 of the other button member.

10 Fixed in the sleeve 32 is a plug 35 having a chamber 36 in its outer end and provided with a bulbous projection 37 connected by a contracted neck 38.

15 Fixed to the inner side of the backing plate 27 is a cylindrical rod 39 extending slidably through the plug 35 and its projection 37 to abut the inner side of the spring 21 and encircling the rod is a coiled compression spring 40, one end abutting the 20 backing plate and the other the bottom of the recess 36.

25 In operation, when it is desired to connect the two members, the extending portion of the plug 35 and the bead 34 are passed through an opening in the article to which the button is to be attached, and the mating member B pressed over the plug from the opposite side of the article.

30 Contact of the bulb 37 with the arcuately curved spring fingers or prongs 22 causes the socket formed by them to recede, depressing the spring 20 until the ends of the prongs clear the sleeve 16, permitting them to expand and thereafter grip the bulb securely.

35 Attempts at separation are unavailing, except by exertion of sufficient force to cause destruction, due to the fact that the bulb 37 cannot pass out of the socket fingers, by reason of their inability to open, being held 40 rigidly constrained by the sleeve 16 surrounding their outer ends.

45 The button is however readily separated by pressing the face 25 inwardly, causing the rod 39 to press the spring 20 and attached socket rearwardly, clearing the sleeve whereupon the button is forced apart by continued pressure on the face 25.

50 Although I have described my improvements with considerable detail and with respect to certain particular forms of my invention, I do not desire to be limited to such

details since many changes and modifications may well be made without departing from the spirit and scope of my invention in its broadest aspect.

55 Having thus described my invention, what I claim as new and desire to secure by Letters Patent is:—

1. A separable cuff button comprising a pair of inwardly converging members having level fixed and movable flat faces respectively, means for retaining said movable face normally extending uniformly with the fixed face, cooperative resilient finger means to cause positive interengagement of said members whereby they are held inseparable, and means actuated by depression of said movable face to release said engaging means.

2. A separable cuff button comprising a pair of inwardly converging members having level fixed and movable flat faces respectively, a spring supported yieldable socket carried by the fixed faced member, a sleeve to prevent said socket from expanding when pressed outwardly by its spring support, a bulbous element carried by the other member to engage in said socket and resist forcible separation, and means actuated by depressing the movable face of the last named member to retract said spring supported socket and release said bulbous element.

3. A separable cuff button comprising a pair of members having level uninterrupted fixed and movable flat faces respectively, a spring to retain said movable face extended, a converging casing reaching inwardly from each member having a clamp member at its inner end, said clamp members being juxtaposed when the button is in operative position, a resilient support on the inner side of said fixed face member, a split spring socket carried by said support, means to prevent expansion of said socket when extended, a bulbous element carried by the other member adapted to engage in said socket under pressure, and a rod passing through said bulbous element to retract said support, said rod being actuated by said movable face.

95 In testimony whereof I have hereunto affixed my signature.

MORRIS O. NOBBE.
